UNITED STATES PATENT OFFICE

140,329

DESIGN FOR A HATCHET

Vine Stoddard, Jesup, Iowa

Application November 4, 1944, Serial No. 116,142

Term of patent 7 years

(Cl. D93—4)

To all whom it may concern:

Be it known that I, Vine Stoddard, a citizen of the United States, residing at Jesup, in the county of Buchanan and State of Iowa, have invented a new, original, and ornamental Design for a Hatchet, of which the following is a specification, reference being had to the accompanying drawing, forming part thereof.

Figure 1 is a side elevational view of a hatchet showing my new design,

Figure 2 is a top plan view thereof, and Figure 3 is an end elevational view thereof.

I claim:

The ornamental design for a hatchet, as shown.

VINE STODDARD.
